UNITED STATES PATENT OFFICE.

SIMON A. HUNTER, OF GRIFFIN, SASKATCHEWAN, CANADA.

WRENCH.

1,164,815.

Specification of Letters Patent. Patented Dec. 21, 1915.

Application filed May 15, 1915. Serial No. 28,486.

To all whom it may concern:

Be it known that I, SIMON A. HUNTER, a citizen of the United States, residing at Griffin, in the Province of Saskatchewan and Dominion of Canada, have invented certain new and useful Improvements in Wrenches, of which the following is a specification, reference being had to the accompanying drawings.

This invention comprehends certain new and useful improvements in wrenches and relates particularly to a wrench designed for use in holding a harrow tooth or the like stationary while the fastening nut is screwed on or off.

The invention has for its primary object a durable and efficient construction of device of this character, the parts of which are so arranged that they may be readily adjusted.

according to the particular length or size of tooth to be attached or detached and the invention further aims to generally improve devices of this class so as to render them more useful and commercially desirable.

With these and other objects in view, as will more fully appear as the description proceeds, the invention consists in certain constructions, arrangements and combinations of the parts that I shall hereinafter more fully describe and claim.

For a full understanding of the invention, reference is to be had to the following description and accompanying drawing, in which—

Figure 1 is a side elevation of a wrench constructed in accordance with my invention, the wrench being shown in applied position. Fig. 2 is a detail perspective view of the brace employed. Fig. 3 is a sectional view of the head. Fig. 4 is a detail view of the handle. Fig. 5 is a detail perspective view of one of the reducers, and Fig. 6 is a side elevation of the socket with a portion of the shank shown in section.

Corresponding and like parts are referred to in the following description and designated in all of the views of the accompanying drawing by like reference characters.

Referring to the drawing, the numeral 1 designates the shank of my improved wrench, a handle 2 being connected by a nut 3 or similar fastening device to one end of said shank, and extending in opposite direction therefrom, as clearly illustrated in the drawing, the opening in the handle through which the shank 1 extends being squared or

otherwise non-circular in formation. The other end of the shank 1 has secured to it or formed integral therewith the head 3 of the wrench, the same being formed with a socket 60 to receive the nut which fastens the harrow tooth in place.

In order to hold the tooth firmly while the nut is screwed on or off, I provide a brace 4 which embodies a longitudinally extending portion 5, one end of which is turned laterally as at 6, and is provided at its extremity with an apertured eye 7 loosely mounted upon the shank 1, the other or lower end of the brace 4 being also laterally 70 turned and constituting a foot 8 which is forked or bifurcated, as indicated at 9, whereby it may receive and straddle the harrow tooth and hold the same firmly while the fastening nut is applied or being removed.

A set collar 10 is mounted upon the shank 1, and is designed to be secured thereon in different positions by means of a set screw 11, said collar being disposed underneath 80 the eye 7 and brace 4, whereby it may be adjusted up and down and the forked foot 9 held in the required position to engage the harrow tooth, according to the length or size of the latter.

From the foregoing description in connection with the accompanying drawing, the operation of my improved wrench will be apparent. In the practical use of the device, the set collar 10 is adjusted, according 90 to the size of harrow tooth to be removed or attached, whereby the brace 4 will have its foot 9 properly engaged with the tooth and as the brace and shank 1 are loosely connected together so far as the rotatable movement of the latter is concerned, it will at once be understood that by turning the handle 2 and the head 3 which is operatively connected thereto, the nut received in the socket of the head may be easily screwed 100 off or onto the tooth.

Preferably, in order to provide for nuts of different sizes, reducers are provided. These are preferably in the form of angular plates 12 which are designed to be received in the 105 socket of the head 3 and secured in place therein by set screws 12a.

While the accompanying drawing illustrates what I believe to be the preferred embodiment of my invention, it is to be understood that the invention is not limited thereto, but that various changes may be

made in the construction, arrangements and proportions of the parts without departing from the scope of the invention as defined in the appended claims.

5. What is claimed, is:

1. A wrench of the character described, comprising a shank provided at one end with a work receiving head, a collar adjustably mounted on said shank, and a brace loosely mounted upon the shank above said collar and provided below the head with a bifurcated foot, for the purpose specified.

10. 2. A wrench of the character described, comprising a shank provided at one end with a handle and at its other end with a head having a socket formed therein for the reception of a nut, a brace formed at one end with an apertured ear loosely mounted upon the shank and at its other end with

15. 3. A wrench of the character described, comprising a shank provided at one end with a bifurcated foot adapted to engage the work, and a set collar adjustably mounted upon the shank between the head and the apertured ear, as and for the purpose set forth.

20. 4. A wrench of the character described, comprising a shank provided at one end with a work receiving head, a brace loosely mounted upon the shank and provided with a work engaging foot, and means for holding the brace in different positions upon the shank.

25. with a handle and at its other end with a head formed with a socket, a brace having one end laterally extended and formed with an ear loosely mounted upon said shank, and at its other end with a laterally extending bifurcated foot adapted to engage the work, a collar adjustably mounted upon said shank between the head and the ear, and a set screw working through said collar and designed to hold the same in adjusted position on the shank, as and for the purpose specified.

30. 4. A wrench of the character described, comprising a shank provided at one end with a work receiving head, a brace loosely mounted upon the shank and provided with a work engaging foot, and means for holding the brace in different positions upon the shank.

35. In testimony whereof I hereunto affix my signature in the presence of two witnesses.

40. SIMON A. HUNTER.

45. Witnesses:

WILLIAM C. WHEWELL,
ADAM G. ROBERTSON.
